(57) **CLAIM**

(21) Appl. No.: **29/159,623**

The design for voice recorder and player having digital camera, substantially as shown and described.

(22) Filed: **Apr. 24, 2002**

DESCRIPTION

(30) **Foreign Application Priority Data**

Nov. 9, 2001 (JP) 2001-033066

FIG. 1 is a front view.

(51) LOC (7) Cl. **14-01**

FIG. 2 is a left side view.

(52) U.S. Cl. **D14/168; D14/167; D16/208**

FIG. 3 is a right side view.

(58) Field of Search D14/156-157,

FIG. 4 is a top plan view.

D14/160-165, 167-168, 188-189, 217-218,

FIG. 5 is a bottom plan view.

299, 496; D16/202, 208; 312/7.1; 369/75.1,

FIG. 6 is a rear view; and,

75.2, 77.1, 77.2; 455/344, 347-351

FIG. 7 is a right, top, front perspective view.
